ANIMAL OILER

Maurice O. Gould, Box 53, Minden, Nebr. 68959, and
Kenneth A. Wendt, 2021 Broad St., Fremont, Nebr.
68025

Filed July 18, 1972, Ser. No. 272,981

Term of patent 14 years

Int. Cl. D30—99

U.S. Cl. D30—99

FIG. 1

FIG. 2

FIG. 3

FIG. 1 is a perspective view of an animal oiler showing our new design thereof;

FIG. 2 is a front elevational view thereof, the rear elevational view being a mirror image thereof; and

FIG. 3 is a top plan view thereof.

We claim:

The ornamental design for an animal oiler, substantially as shown.
